DUPLICATING MACHINE

Rowland Leigh Kelly, Chicago, Ill., assignor to
Ditto, Incorporated, a corporation of West Virginia

Application August 7, 1935, Serial No. 35,112

10 Claims. (Cl. 101—133)

The invention relates to duplicating machines and is particularly adapted to be embodied in duplicating machines of the type shown and described in U. S. Letters Patent No. 1,972,681 granted September 4, 1934 to James K. Duncan.

One form of the invention is embodied in a duplicating machine which comprises a bed plate over which a hectograph band is stretched. A cover for the machine comprises two sections, one of which has one end pivoted to the frame of the machine and the other of which is pivoted to one end of the first-mentioned section. The second section carries an impression or platen roller adjustably secured to the section. Hinged to the frame is means for holding a plurality of copy sheets. Paper guiding means is provided on the second section to guide the copy sheets to a position wherein the impression or platen roller may engage them and apply them to the hectograph band. The operator may withdraw the copy sheets one by one manually from the copy sheet holding means and place them in the paper guiding means. The operator accomplishes the feeding of copy sheets with one hand while the other hand is employed to reciprocate the impression or platen roller.

Other objects and advantages will become apparent as the following detailed description progresses, reference being had to the accompanying drawings, wherein—

Fig. 1 is a plan view of a duplicating machine which embodies the invention.

Fig. 2 is a section taken on line 2—2 of Fig. 1, the section being taken through one section of a member which serves as a closure member for the duplicating machine and also as a means for holding the impression or platen roller.

Fig. 3 is a section taken on line 3—3 of Fig. 1, the closure member being shown in full lines in a partially opened position and in dotted lines in a more fully opened position, and

Fig. 4 is a section taken on the same line as Fig. 3 but showing a closure member in its closed position.

The duplicating mechanism per se is shown in more detail and is described more fully in U. S. Letters Patent No. 1,972,681. Briefly, the machine comprises a case or box-like frame formed of side members 10 and 11, an end member 12 provided with a handle 13 and a spring clip 14, a removable end member 15 provided with a retaining clip 16 and a base 17.

The frame comprises a bed plate 22 extending between the side members 10 and 11 and terminating short of the end members 12 and 15. The

bed plate is a support for a hectograph or duplicating band 23 which has its ends detachably secured to spindles 25 journaled in the side members 10 and 11. The spindles 25 have knurled wheels 26 whereby the operator imparts rotation to the spindles to unwind the duplicating band 23 from one spindle and wind it upon the other.

The cover for the frame carries an impression or platen roller 43 and is formed of two sections 36 and 37, the section 36 being provided with depending flanges 38 whereby one end of the depending section 36 is pivoted to the frame by screws 39 which pass through openings in the flanges 38 and are screw-threaded into portions 40 formed integral with the frame. The section 37 is provided with depending flanges 41 and is hinged as at 42 to the section 36. At its free end, the section 37 carries the impression or platen roller 43 which is journaled in depending lugs 44. The handles 45 are secured to the flanges 41, one 20 of these handles 45 being grasped by the operator when the machine is operated.

The section 37 is provided adjacent its free end with a relatively large aperture 37a which is formed by stamping a lip or paper guide 50 downwardly from the material, preferably sheet metal, from which the section 37 is formed. The paper guide 50 is slightly dished as at 52 at its center and is provided with spaced slots 53 extending transversely of the section 37. The slots 53 accommodate paper guides 54 which are flattened on one side to form guiding edges for copy sheets and are held in adjusted positions in the slots by nuts 55. To complete the hopper through which the copy sheets are fed to the impression roller 43, a guard 56 is secured to the free end of the section 37 and prevents the copy sheets from coming into contact with the upper part of the roller 43.

When the impression or platen roller 43 is reciprocated over the bed plate 22, the sections 36 and 37 have a jack-knife action with the section 36 pivoting on the frame, while the section 37 pivots on the free end of the section 36. To limit the spread operative position of the cover section when it is employed in a duplicating operation, links 57 are pivotally secured at 58 to the flanges 41 and by means of inclined slots 60 and pins 61, are connected operatively to the section 36. It will be noted that each slot 60 terminates in an offset portion or slot 62 which forms a shoulder so that the spread position of the sections is limited. However, by actuation of the links 57, the pins 61 may be caused to enter the offset slots 62, whereupon the cover compris- 55

ing the sections 36 and 37 can be elongated completely to form a closure means for the frame as shown in Figs. 1 and 4. With the sections 36 and 37 in the positions wherein they are shown in full lines in Fig. 3, the platen roller 43 is located on supporting blocks 63 pivoted at 64 to the frame. The blocks have a margin bar 65 secured thereto.

The section 36 is provided with means for holding a stack of copy sheets which are shown in dotted lines at 70 in Fig. 3. This means comprises a bar bent to form an open-sided pocket 72 having an upper wall 73 and a bottom wall 74 as well as an end wall 75. It will be noted that the end wall 75 is not at right angles to the walls 73 and 74 which are preferably parallel to each other, the construction being such that when a stack of copy sheets are positioned as shown in dotted lines in Fig. 3, the forward ends thereof will be in staggered relationship so that they can be readily grasped and separated by the operator. The sides of the copy sheets are engaged by guide members 71 preferably formed from sheet metal, the guide members 71 having tapered tongue-like portions 78 which engage the upper side of the stack of copy sheets 70 and assist the wall 73 to hold the stack in place upon the section 36.

The pocket 73 is secured adjustably to the section 36 by a pin 79 which rides in a slot 80 provided in the section 36, the pin 79 being in frictional engagement with the section 36 so that the pocket 73 will remain in positions in which it is adjusted by the operator. In a like manner, the paper guides 71 are secured adjustably to the section 36 by pins 82 which ride in slots 83 formed in the section 36. The pins 82 also engage the section 36 frictionally and hold the paper guides 71 in the positions in which they are adjusted by the operator.

The machine is provided with means (not shown) holding the gelatin band in a stretched condition over the bed plate. The construction of this means as well as other construction of the improved machine is shown in detail in U. S. Letters Patent No. 1,972,681.

The operation of the improved duplicating machine is substantially as follows: The operator reciprocates the platen roller 43 by grasping one or both of the handles 45 and by pushing it or them back and forth. A collapsed position of the cover is shown in dotted lines in Fig. 3. At the beginning of each cycle of operations, the operator withdraws the top copy sheet 70 from the stack thereof carried by the section 36 and brings its forward edge forwardly and downwardly so that it passes between the paper guide 50 and the guard 56 to engage the margin bar 65 as illustrated in full lines in Fig. 3. The operator then reciprocates the platen roller 43 after which the copy sheet is removed from the hectograph band.

It has been discovered that by placing the copy sheet holding means upon the section 36 instead of upon the section 37, an extremely large saving of time is effected and the operator can perform the feeding operation with comparatively little effort.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

I claim:

1. A duplicating machine comprising a bed plate, a member having one of its ends hinged adjacent one end of said bed plate, a second member pivoted to the first-mentioned member, impression means carried by said second member and adapted to be reciprocated over said bed plate, and means mounted on the first-mentioned member for holding a stack of copy sheets.

2. A duplicating machine comprising a bed plate, a cover for said bed plate formed of a plurality of sections, one of said sections being pivoted at one end adjacent said bed plate, another of said sections being pivoted to the first-mentioned section, impression means carried by said other section and adapted to be reciprocated over said bed, and means carried by the first-mentioned section for holding a stack of copy sheets.

3. A duplicating machine comprising a bed plate, a cover plate having one end pivoted adjacent one end of said bed plate, a second cover plate hinged to the free end of the first-mentioned cover plate, impression means carried by said second cover plate and adapted to be reciprocated over said bed, and means carried by the first-mentioned cover plate for holding a stack of copy sheets.

4. In a duplicating machine, a box-like frame, a bed plate carried by the frame and provided with a duplicating surface, a closure member for said box-like frame, said closure member comprising a section having one end pivoted to the frame and a second section pivoted to the first-mentioned section, a platen roller carried by said second section, and means carried by the first-mentioned section for holding a stack of copy sheets.

5. A duplicating machine comprising a bed plate, a member having one of its ends hinged adjacent one end of said bed plate, a second member pivoted to the first-mentioned member, impression means carried by said second member and adapted to be reciprocated over said bed plate, and means mounted on the first-mentioned member for holding a stack of copy sheets in staggered formation.

6. A duplicating machine comprising a bed plate, a cover for said bed plate formed of a plurality of sections, one of said sections being pivoted at one end adjacent said bed plate, another of said sections being pivoted to the first-mentioned section, impression means carried by said other section and adapted to be reciprocated over said bed, and means carried by the first-mentioned section for holding a stack of copy sheets in staggered formation.

7. In a duplicating machine, a box-like frame, a bed plate carried by the frame and provided with a duplicating surface, a closure member for said box-like frame, said closure member comprising a section having one end pivoted to the frame and a second section pivoted to the first-mentioned section, a platen roller carried by said second section, and means carried by the first-mentioned section for holding a stack of copy sheets in staggered formation.

8. A duplicating machine comprising a bed plate, a member pivoted adjacent said bed plate, a second member pivoted to the first-mentioned member, a platen roller carried by the second member and adapted to be reciprocated over the bed plate, means carried by said second member

for guiding copy sheets to said platen roller, and means carried by the first-mentioned member for holding a stack of copy sheets.

9. A duplicating machine comprising a bed plate, a cover plate having one end pivoted adjacent one end of said bed plate, a second cover plate hinged to the free end of the first-mentioned cover plate, impression means carried by said second cover plate and adapted to be reciprocated over said bed plate, means carried by said second cover plate for guiding copy sheets to said impression means, and means carried by

the first-mentioned cover plate for holding a stack of copy sheets.

10. A duplicating machine comprising a bed plate, a member having one of its ends hinged adjacent one end of said bed plate, a second member pivoted to the first-mentioned member, impression means carried by said second member and adapted to be reciprocated over said bed plate, and means mounted on one of said members for holding a stack of copy sheets in staggered formation. 5 10
